UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

PNEUMATIC PUMP.

Application filed September 10, 1921. Serial No. 499,816.

To all whom it may concern:

Be it known that I, BURTON S. AIKMAN, a citizen of the United States, residing at Milwaukee, in the county of Milwaukee and 5 State of Wisconsin, have invented a certain new and useful Improvement in Pneumatic Pumps, of which the following is a full, clear, concise, and exact description, reference being had to the accompanying drawings, forming a part of this specification.

My invention relates to pneumatic pumps.

The present invention relates to the same general subject matter as my prior application, Serial No. 50941 and my prior patents 15 particular Nos. 1,356,684, 1,359,945, 1,357,671 and reissue No. 14,946 upon which the present construction is an improvement.

The aim of the present invention is to provide a pneumatic pump of the greatest 20 possible reliability and certainty of operation. Reliability is the fundamental requirement and it must be secured because an unfailing water supply is an essential requirement for animal and human existence. 25 Where reliance is placed upon a pneumatic pump for supplying water to the farmer and his stock, it is generally done because of the superior quality of the water so furnished, namely, fresh from the well as it is called for. But this fresh from the well character 30 of the system is an unmixed blessing only if the system is dependable and operates invariably upon demand. Since the water is drawn from the well only as it is used there 35 is no storage or reserve. Hence, failure of the pump is felt immediately and keenly.

In producing the pump of the present invention I have followed air brake practice as far as possible since this art of air brakes 40 has been developed to a point of almost unbelieveable reliability. Simplicity is of course desirable since it tends to greater reliability and lower cost.

In the present pump I believe I have developed a simpler and more rugged pump 45 than any now on the market. I have avoided mechanical connections and mechanical operating parts wherever possible and have depended upon pneumatic elements of proven type and character because I find that greater reliability results from the use

of fluid pressure transmission than mechanical transmission. I have largely dispensed with springs. The parts have been so designed and arranged as to minimize the evil 55 effects of sand, dirt, grit or other impurities in the water. Due to the pneumatic transmission instead of mechanical transmission, the controlling valves of the pump may be placed at the head of the well or at the pump 60 as desired.

The valve mechanism and head of the pump present certain novel features in themselves.

The float which I employ as a controlling 65 member for unbalancing pressures for the several valve members is of a novel character as will be more apparent from the following description:

There are other novel features to which 70 attention will be called in the following specification and claims:

In order to teach those skilled in the art with the manner of constructing and operating my invention, I shall now describe in 75 connection with the accompanying drawings certain embodiments of the invention.

In the accompanying drawings:

Figure 1 is a vertical axial section of the head and upper end of the barrel of a 80 pump embodying my invention;

Figure 2 is a similar view of the foot casting and the lower end of the barrel of the pump shown in Figure 1;

Figure 3 is a top plan view of the pump; 85

Figure 4 is a horizontal section of the

head taken on the line 4—4 of Figure 1;

Figure 5 is a longitudinal vertical section of the head taken on line 5—5 of Figure 3;

Figure 6 is a side elevation as viewed from 90 the right of Figure 1;

Figure 7 is a fragmentary section of the head showing the position of the exhaust port and the exhaust valve 10;

Figure 8 is a horizontal section through 95 the head taken on line 8—8 of Figure 1;

Figure 9 is a rear elevation of the head casting showing the seat for the diaphragm cap;

Figure 26 is a horizontal section of the head casting taken on the line 26-26 of 50 Figure 20;

Figure 27 is a right side elevation of the head casting shown in Figure 25;

Figure 28 is a fragmentary section of the head taken on the line 28-28 of Figure 25;

Figure 29 is a horizontal section similar 55 to Figure 26 taken on the line 29-29 of Figures 20 and 27; and

Figure 30 is a diagrammatic layout of a 60 system employing a pump embodying my invention.

Referring now to Figure 30 it will be seen that I have herein indicated in diagrammatic form a system embodying my invention. The pump 1 is submerged in the

water of the well 2, this pump having three 65 connections thereto, namely, the water discharge pipe 3, the air supply pipe 4 and the exhaust connection 5. The water discharge pipe 3 contains a check valve 6 which check valve may be mounted in the head of the 70 pump if desired, as will be explained in detail later. The discharge pipe 3 leads to an air chamber which is known as a steady flow chamber 7 of a construction shown in my copending application, Serial No. 456,842 75 filed March 30, 1921. This steady flow chamber preferably embodies a second check valve for maintaining the pressure of an air bubble or cushion in the chamber 7. From thence, the discharge pipe 3 leads to 80 the distributing pipes 8 and 9, the pipe 8 leading to a faucet 10 in connection with the water or plumbing system of a house or the like. The distributing pipe 9 leads to a water connection controlled by a cock or 85 valve 12 such as may be suitable for watering stock, sprinkling purposes or whatever else is deemed desirable. The pump 1 is operated from the compressed air stored in the reservoir 13, this reservoir being periodically charged with air under pressure from the compressor 14, which compressor is 90 driven by the electric motor 15 or other suitable source of motive power.

The electric motor is controlled by a suitable controller 16 which serves also as a shut-off valve in the delivery pipe 17 between the compressor and the storage tank or reservoir 13. The particular construction of this controller 16 is shown in my co-pending application Serial No. 456,843, filed March 30, 1921, and it operates to cut in the compressor when the pressure in the main reservoir 13 drops to a predetermined minimum and serves to cut off the compressor when the pressure in said reservoir rises to a predetermined maximum. The delivery pipe for compressed air from the tank 13 passes through a control valve 18 which control valve has a connection 19 running therefrom back to the controller 16. This control valve 18 operates normally as a reducing valve for reducing the pressure on the pump 1, but it is manually operable to impose the full pressure of the reservoir 13 upon the pump 1 110 for fire purposes, or it may be employed to start the compressor 14 in order to raise the pressure in the tank 13 for the purpose of pumping up automobile tires and the like by way of pipe 20. This particular control valve and its function is explained in my copending application, Serial No. 493,566 filed Aug. 19, 1921, now Patent No. 1,462,842.

One embodiment of the invention is shown in Figures 1 to 14, inclusive. This pump comprises the head member 21 and the foot member 22 between which head and foot members a piece of tubing, preferably brass or bronze

tubing 23 is connected. The head member and foot member are connected together by tension elements including the water discharge pipe 24, the control valve casing 25, 5 and the hollow stud member 26 with the nut 27 upon the lower end thereof. These members which are placed in tension thrust the head and foot members towards each other upon the ends of the tube 23 thereby compressing the gaskets 28 and 29 to form a 10 tight fit.

The foot member 22 has an inlet check valve 30 seating upon a pair of annular seats 31 and 32 for closing off the annular water 15 space 33 which communicates with the water in the well through a screen 34 which is held in place by the nut 27. The nut 27 is adapted to form a water tight connection with the sleeve 35 which, at its upper end, forms the 20 annular valve seat 32. The valve 30 is of relatively large area and has a small lift, thereby reducing the pounding of this valve when the pressure is applied for expelling the water from the pump. Thereby, the 25 wear on this valve is materially decreased. The water discharge pipe 24 is threaded at its lower end into the control valve casing 25 and communicates with the lower end of the pump chamber through the annular port 36 30 which has the double valve seat 37 surrounding the same.

The housing 25 contains a water chamber 38 which is closed at its lower end by the 35 flexible diaphragm 39, this diaphragm being clamped at its edges between the two circular blocks 40 and 41. The circular blocks 40 and 41 are set in a counterbore in the lower end of the casting forming the housing 25 and the blocks 40 and 41 are relieved to form 40 a circular channel 42 extending completely around the adjacent end of these blocks. The block 40 has a series of valve ports, three 45 in number preferably, one of these valve ports being shown at 43 communicating with a passageway 44 which in turn connects with the annular passageway 42. The lower block 41 is threaded into the lower end of the housing member 25 to clamp the diaphragm 39 firmly, and this block has a number of 50 radial arms running to a central hub 45, this hub being bored out and threaded to receive the upper end of the hollow stud 26. A passageway 46 is drilled through the interior of the hollow hub and connects the 55 passageway 42 with the passageway 47 running through the hollow stud 26. It will be noted that the passageway 47 extends through the stud 26 to the outside of the pump, that is, into the well.

60 The diaphragm 39 is clamped between two plates or heads 48 and 49 by the stem 50, which stem is connected at its upper end to a valve 51 having a yielding face 52 adapted to cooperate with the three relief ports 43 65 previously explained. The stem 50 extends

upwardly through a central hub member 53 formed in the block 40, this hub member being connected to the periphery by radial arms through which are drilled the passageways 44. Thus, the pressure prevailing in 70 the chamber 38 has free access to the upper side of the diaphragm 39 and the pressure within the pump chamber has free access to the lower side of the diaphragm 39. I find that the valve 51 closes automatically 75 because of the weight thereof and the weight of the diaphragm, but I may employ a spring set in the recess in the hub member 53. The internal pressure also tends to hold the valve 51 against the valve ports 43 until 80 the diaphragm 39 is forced upwardly to open the valve 51 whereby the pressure in the chamber 38 is discharged into the well.

The valve port 36 through which the water is discharged from the pump chamber into the discharge pipe 24 is adapted to be controlled by a float member 55. The construction of this float member is novel in itself. It comprises a central cork body 56 90 of hollow cylindrical form protected by rubber walls 58 completely enclosing the same. Flat rubber discs 59 and 60 are connected by relatively thin necks 61 and 62 to the main body of the float to render these rubber faces or valve members relatively flexible 95 and yielding in order to cooperate properly with the corresponding valve seats. Hard rubber guides in the shape of short cylindrical sleeves 63 and 64 are vulcanized on the inside of the bore of the float and they serve 100 to guide the float upon the pipe 24.

A metal ring 65 preferably of copper is placed about the neck 62 connecting the valve member 60 to the main body of the float, this construction being employed to give sufficient weight to the float and yet providing a soft yielding face which is adapted to close off completely the port 36 even though the same be slightly irregular or not exactly at right angles to the face of 110 the valve member 60.

A ring of soft rubber is placed at 66 in a corresponding position with respect to the valve member 59. This rubber ring is employed to provide a yielding backing for the valve disc 59. The upper valve ring or disc 59 cooperates with a similar annular valve port 67 having the double valve seat 68 formed at the lower side of the head member 21.

The head member 21 is provided with suitable pipe connections for the pipes 3, 4 and 5, the water discharge pipe 3 being threaded into a suitable socket 88 and communicating by way of a diagonal passageway 89 with the upper end of the water discharge pipe 24. As previously explained, a check valve may be mounted in the head as shown in Figure 10^a, in this case the socket 88' for receiving the pipe 3 has the ball check valve 130

90 lying immediately below the same, this valve cooperating with a valve seat 91 which has a small leakage passageway 92 cut in the seat thereof for the purpose of insuring reversal of the pump as will be explained later. This score or leakage passageway may be omitted, but I prefer to apply the same in order to insure reversal of the pump. The head of the pump also provides a threaded socket 93 to which is connected the exhaust pipe 5. The exhaust pipe 5 communicates through the head of the pump with a relatively restricted passageway 94 lying immediately above the annular valve port 95 which valve port is provided with the two surrounding annular valve seats 96 and 97. The valve port 95 is controlled by the exhaust valve 98 which has a yielding face 99 for cooperating with said seats 96 and 97. The valve port 95 opens into a chamber 100 in which the exhaust valve is mounted, the chamber being closed off on one side by the flexible diaphragm 101, the diaphragm being clamped between the back of the exhaust valve 98 and a follower plate 102 by means of the valve stem 103, which stem is guided in a closely fitting bore formed through the head member 21 and which stem carries at its opposite end the admission valve member 105 to control the admission of motive fluid to the pump chamber as will be described more in detail later.

A pressure chamber 106 is formed within a cap member 107 on the outer side of the diaphragm 101, this chamber 106 communicates with a passageway 108—109 which is drilled through the boss 110 on the cap member 107. (See Figures 11 and 12). The passageway 109 communicates through the wall of the head with the water passageway 89 communicating with the water discharge pipe of the pump. In other words, the diaphragm 101 is subjected on the left side, as viewed in Figures 1 and 5, to the pressure of the water in the water discharge pipe 4 and passageway 89, while the diaphragm is subjected on the right hand side in the chamber 100 to the pressure of the working fluid prevailing in the top of a pump chamber. The pressure chamber 100 in which the exhaust valve 98 is mounted communicates with the upper end of the pump chamber through the passageway 111 and the annular valve port 67.

A small leakage passageway 112 may be drilled through the side walls of the outer valve seat 68 to permit the float to leave the valve seat more readily if desired. This leakage port is optional.

The air supply pipe 4 as shown on Figure 20 is threaded into the socket 113 and communicates by way of a passageway 114 with a chamber 115 formed in the head of the pump. The chamber 115 is closed at its

outer end by the screw 116 which plugs the opening formed during the machining operation of the head. The admission valve 105 seats upon a valve seat 117 which separates the chamber 115 from the port 118. The port 118 communicates with the top of the pumping chamber.

The valve seat 117 is provided with a score 117' shown in exaggerated form in Figs. 1, 5, 17 and 20 to permit a certain amount of air to leak past when the valve 105 is closed. Instead of this arrangement a small hole may be drilled through from the chamber 115 to the passageway 118. The purpose of the score 117' is to permit a small amount of air to flow past the air admission valve to insure reversal when the water has filled the pump chamber. The score on the valve seat is preferable since it is self cleaning at each operation of the valve.

The operation of this form of my invention is as follows: Assuming that the pump is properly supplied with compressed air and assuming that the pump is submerged in liquid sufficient to fill the same continuously, let it be assumed that the exhaust valve has just been opened and the admission valve closed, and that the inlet valve 30 will now open to refill the pumping chamber. The inlet check valve 30 may be provided with a relatively flexible spring to normally hold the same closed, but as I have shown the pump such a spring is not essential. The check valve 30 opens and the submergence pressure of the water in the well forces the water up around the annular passageway 120 around the control valve body 25 raising the float. As the level of the water rises to a point where the float engages the annular valve seat 68 about the port 67, the sudden closing of this port shuts off further discharge of air from the pumping chamber and the inrushing water both due to the submergence pressure and to the inertia of movement creates a pressure in the pumping chamber which is transmitted through the ports 36 through the control valve chamber 38 thereby insuring first the closing of the relief valve 51 and tending to increase the pressure on the left side of the diaphragm 101 to close the exhaust valve and open the admission valve. That is to say, the reversal of the valves may be accomplished solely by this submergence pressure. I have provided, however, for reversal of the valves independently of the submergence pressure, and this comprises the leakage passageway on the valve seat 117. When the float 56 rises it closes off the port 67 so that no further exhaust air can escape by way of the exhaust valve. The air which then leaks past the admission valve 105 tends to create a pressure upon the top of the water in the pump chamber, which pressure is transmitted to the diaphragm 101, on the side of

120
125
130

the chamber 106. The area of the diaphragm 101 as compared with the area of the valve 105 is such that the valve 105 is quickly started from its seat opening the 5 same and closing the exhaust valve 98. The pressure of the live air on top of the water begins to force the water down through the passageway 36 out the discharge pipe 24, the passageway 89 and through the water discharge pipe 3. During this discharge, the 10 pressure of water above and below the diaphragm 39 is substantially equal so that there is no tendency for the diaphragm to operate the valve 51. However, the valve 15 51 is held to seat with the pressure of the water because the valve ports 43 open to the outside and thus the pressure of the liquid on the inside tends to hold the valve 51 closed. As soon as the level descends to 20 a point where the valve member 60 on the lower part of the float 55 closes off the port 36 a different pressure will immediately be created. The rise of pressure of the motive fluid in the pump chamber operates upon the 25 lower side of the diaphragm 39 and forces the control valve 51 upwardly opening the port 43 and permitting relief of the pressure in the chamber 38. By the opening of the valve 51 a certain part of the liquid 30 from the chamber 38 to escapes through the port 43, passageways 44, 42, 46, 47 to the exterior of the pump into the well so that the pressure within the discharge pipe 24 and the chamber 38 drops to substantially zero 35 or to submergence pressure. This drop of pressure is transmitted through the port 109 to the diaphragm chamber 106 on the lefthand side of the diaphragm 101. Since the pressure of the motive fluid within the 40 pump has access to the right side of the diaphragm 101 by way of the port 67, passageway 111, chamber 100, the drop in pressure in the chamber 106 is followed by an immediate movement of the diaphragm 45 101 to the left thereby opening the exhaust valve 98 and closing the admission valve 105 with a quick snap movement. The opening of the exhaust valve 98 is accompanied by an immediate drop in pressure of the 50 motive fluid in the pump chamber. The discharge exhaust passageway 94 may be slightly restricted in order to insure that the diaphragm 101 will attain a slight pressure while the level of water is rising to fill the 55 pump. Naturally, as soon as the pressure of motive fluid in the pumping chamber drops below submergence pressure, the water enters by way of the check valve 30, raises the float 55 from the valve port 36 and moving the float upwardly until the upper valve member 59 attached to the float 55 closes off the valve seat 68. During the time of filling 60 the pump chamber the leak on the seat 117 merely by-passes a small amount of live air. 65 This goes out the exhaust passage 111 to at-

mosphere. The pressure of the motive fluid upon the valve 105 tends to hold it in closed position. As soon, however, as the valve member 59 on the float 55 closes the port 67 and exhaust outlet passageway 111, such 70 leakage of live air is prevented from going out the exhaust passageway and operates substantially to create a small pressure upon the liquid trapped in the pumping chamber. This pressure is transmitted through the 75 discharge pipe 24, through the passageway 109, through the diaphragm chamber 106 closing the exhaust valve 98. As a result, the diaphragm 101 is moved to the right as shown in Figure 1 closing the exhaust valve 80 and opening the admission valve. This admits live air freely to the top of the water in the chamber and begins to drive the same out continuously.

The small passageway 112 is provided to 85 fill the passageway 111 and the chamber 100 with air so that the pressure upon opposite sides of the valve member 59 may equalize to let the float drop freely with the level of the water after the pressure of 90 the motive fluid is freely applied to the top of the water.

As previously pointed out, there is a tendency for the submergence pressure to close the exhaust valve and open the check valve 95 and where a submergence of a fair amount is assured, this would invariably be sufficient to reverse the main valve. The relatively narrow annular passageway 120 between the body 25 and the side walls of the pump 100 serve to retard the downward movement of the water to prevent the violent pounding of the intake check valve 30 upon its seat. There is a further tendency of the air admitted by the leakage past the admission 105 valve to cushion the application of the motive fluid at least to the extent of having the intake valve 30 closed before live air is freely admitted to the top of the pumping chamber.

I now wish to call attention to the fact that in this pump not a single spring is employed and yet the pump is positively operative for every condition to which a faucet controlled pneumatic pump may be subjected. If water is withdrawn slowly, there is 115 no danger of a blow-over since the seating of the valve member 60 attached to the float 55 upon the valve seat 37 of the passageway 36 secures a positive differential of pressure 120 between the air pressure and the water pressure and thereby secures operation of the main diaphragm 101 for shifting the main valves.

It will further be observed that I have 125 followed air brake practice and that every valve or control operation is secured through pressure differences and fluid transmission with as little mechanical connection as is possible. First of all, the admission valve

seats with pressure and as soon as it starts to open, it moves completely to open position. The same is true of the exhaust valve. It seats with pressure and tends to maintain itself normally tight, but as soon as it starts away from its seat, it moves very freely and the force which is sufficient to start the valve away from its seat is always ample to force it completely free of the valve port. The main valves, namely, the admission valve 105 and the exhaust valve 98 are operated by a valve motor which operates through differences in pressure on opposite sides of a working diaphragm or piston. The control or relief valve 51 operates in the same manner. In each instance, after the preponderance of pressure starts in a given direction, such start invariably increases the pressure differences so that an action once initiated invariably goes to the final state.

In expelling the water the dropping of the float 55 upon the valve seat first initiates a reduction of pressure on the upper side of the diaphragm 39. This opens the valve and increases the reduction in pressure. The reduction in pressure of the water in the discharge pipe 24 causes a reduction in pressure upon the balanced diaphragm member 101 so that the air pressure starts to move the diaphragm over. In doing so it opens the exhaust valve thereby further calling in the aid of the admission valve 105 which is held to its seat by pressure.

When the float with its connected valve 59 seats against the valve seat 68 during the filling stroke, the pressure on the right side of the diaphragm 101 is decreased, and the pressure on the left side of the same is increased, whereupon the main valve is snapped across in the opposite direction.

I shall now describe the preferred form of the pump illustrated in Figures 15 to 19, inclusive.

In the embodiment of Figures 15 to 19, inclusive, I have placed the controlling valve which I sometimes term the relief valve, in the head since the operation of the diaphragm for this valve is operated by fluid pressure. The principle of operation is substantially identical with that of the embodiment shown in Figures 1 to 14, inclusive. The head member 121 has a threaded socket 122 for connection with the live air pipe, a threaded socket 123 for connection with the exhaust pipe 5, and a threaded socket 124 for connection with the water delivery pipe 3. A controlling float 55 of substantially identical construction with the one previously described is employed in this type of pump. The foot member 125 is of substantially the same design and construction as the foot member of the previously described pump and it employs a similar inlet check valve 30 guided on the stud 126. The pumping chamber is formed on the inside of the length

of seamless tubing 23 and it is held against the gaskets 28 and 29 by the water discharge pipe which threads at its upper end into the head member 121 and at the lower end into the water outlet casing 127 which has a threaded socket 128 at its lower end for receiving the threaded stud 126. A threaded cap threads on the lower end of the stud 126 and presses against the sleeve 35 formed integral with the foot casting 125. A screen 34 is held over the inlet opening.

The water discharge box 127 has three valve ports 130 all of which discharge into the common central chamber 131 which communicates with the lower end of the water discharge pipe 24. These valve ports have circular valve seats 132 which are adapted to be closed off simultaneously by the valve member 60 mounted upon the float 55. I have found that in practice three separate valve seats of this character are preferable to the complete annular seat because of the better sealing which is secured between the lower end of the float and such separate valve seats. These valve seats are three in number and therefore are easily covered by the valve member 60. The head member 121 has on its lower surface the annular port 133 provided with the circular valve seats 134-135, this valve port being adapted to be closed off by the valve member 59 at the top of the float 55 when the water has filled the pump chamber.

The relief or controlling valve structure 136 is mounted in the head of the pump as previously indicated in a position where it is substantially free of all difficulties which might be caused by sand or impurities in the water. This structure comprises an operating stem 137 which is splayed or squared as indicated in Figures 15 and 19 to provide an additional passageway through the guide member 138 for relieving the pressure in the water discharge pipe 24 and connected passageways as will be described later. An operating piston formed by the diaphragm 139 and the clamping heads 140 and 141 is connected to the righthand end of the stem 137 as indicated in Figure 15. The other end of the stem has connected thereto the relief or controlling valve 142, which relief or controlling valve has a yielding face 143 for cooperation with the double valve seat 144 that controls the annular relief passageway or port 145. A helical spring 146 tends to move the diaphragm 139 to the right in Figure 15 for closing the relief valve 142. The relief valve 142 is mounted in a chamber 147 formed partly by a recess in the head casting and partly by a recess in the cap member 148, and this chamber is always in communication with the water discharge pipe 24 by way of the passageway 149. The diaphragm member 139 which is connected to the valve stem 137 for operating the valve 142

is clamped between a cap member 150 and the adjacent portion of the head member. The cap 150 contains a recess or cylinder 151 which communicates by way of the passageway 152—153 with the valve port 133 controlled by the float 55. It will be seen that the diaphragm chamber 151 is adapted to be in communication with the pump chamber and to receive the pressure of the motive fluid during the discharge stroke of the pump. The opposite face of the diaphragm 139 is subjected to the pressure prevailing in the water discharge pipe and in the water discharge passageway 154 since this diaphragm forms a wall across an opening 155 communicating with said water passageway 154. The water discharge passageway 154 is controlled by a ball check valve 156, which ball check valve may also be provided with a leak as previously explained in connection with the prior embodiment.

The annular valve port 145 of the relief valve communicates by way of a drilled passageway 157 and a cooperating passageway 158 with the exhaust connection 123. This exhaust connection has a relatively restricted exhaust passageway 159 which leads to an annular exhaust port 160 having the double seat 161 controlled by an exhaust valve 162 having a yielding face 163 and secured to a flexible diaphragm 164 by means of the valve stem 166 and the follower plate 165. The exhaust valve 162 lies in a recess in the head casting 167, which recess is covered by the diaphragm 164.

The valve chamber 167 communicates by way of the exhaust passageway 170 with the interior of the pump through the port 103 which is surrounded by the double circular valve seat 134—135. The diaphragm chamber 169 which is formed in cap 168 communicates by way of a drilled passageway 171—172 with the water passageway 154 below the check valve 156.

The air connection 122 communicates by way of a short passageway 175 with a chamber 176 the outer end of which is closed by the screw plug 177, this chamber being formed to receive the admission valve 178 which is mounted on the outer end of the valve stem 166. The valve stem 166 having the valve 178 integral therewith fits in a closely fitting bore through the head-casting and connects with the exhaust valve 162 and diaphragm 164 previously referred to. The seat 179 of the admission valve 178 may contain a scratch or groove to permit a leakage of air if desired in order to insure reversal. The valve port 179 communicates with an admission passageway 180 leading to the top of the pump chamber.

It will be noted that I have provided a conical spring 181 for the admission valve 30 and have provided a spring 146 for the

control valve 142, but these springs may be omitted. In fact, I have operated the device without these springs with entire satisfaction.

The operation of this form of the pump is as follows:

Assuming that the discharge stroke has just been completed and that the relief valve 142 has just been opened causing a reduction of pressure in the diaphragm chamber 169 and causing opening of the exhaust valve, the admission valve is closed and the compressed air within the pump escapes through the restricted exhaust passageway 159 holding the exhaust valve open during such discharge and the check valve 30 being opened to permit the water level to rise within the pump chamber. As the water level rises in the pump chamber the float 55 rises with it until the upper valve member 59 strikes the valve seats 134—135 closing off both the exhaust passageway 170 and the diaphragm chamber passageway 153. As a result the submergence pressure is transmitted through the water outlets 130 to the water discharge pipe 24 to diaphragm chamber 169 and to the left side of the diaphragm 139 as shown in Figure 15. At the same time, the exhaust valve 164 is closed and the admission valve 178 is opened. This begins the discharge stroke. Assuming however, that the submergence pressure was insufficient to shift the exhaust and admission valves, this may be accomplished either by the leakage of air past the seat 179 of the admission valve 178 which places a small pressure upon the water contained in the pumping chamber, which pressure is not permitted to escape out of the exhaust passageway, nor is it permitted to escape into the diaphragm chamber 151, but instead causes the pressure of the liquid in the pump chamber to act upon diaphragms 139 and 164 closing the relief valve 142 and the exhaust valve 164 and opening the admission valve 178. The result is reversal of the main valve.

I have previously mentioned a leak which may be formed on the seat of the ball check valve 156 on the water discharge line. This may be utilized to secure reversal of the pump instead of a leak on the seat of the admission valve 178.

I have provided a leak in the valve seat 135 as shown at 182 to permit the floating valve 55 to be released from the valve port 133 when the water begins to move out of the pump. As the water is driven out of the pump, it flows out through the valve ports 130 through the chamber 131, pipe 24, through the passageway 154 past the check valve 156 and out to the water line 3. The pressure of the water in this line is transmitted to the left side of the diaphragm 139

as viewed in Figure 15 and to the left side of the diaphragm 164 as viewed in Figure 17, thereby holding both of these valves closed. Air pressure of substantially the same value acts upon the opposite sides of these diaphragms, but due to the fact that the effective area in each case is in favor of the water pressure the valves are closed. In the case of the control valve 142 the water pressure tends to force the valve against its annular seats 144 because the port 145 communicates with the exhaust passageway. The result is that the valve is held to its seat by pressure and since the pressures of water and of air upon the two sides of the diaphragm 139 are substantially equal the preponderance is now in favor of holding the valve to seat. In the same way, the exhaust valve 162 seats with pressure against the exhaust port 160 and the pressures upon the two sides of the diaphragm are substantially equal with the result that during this stage of operation the exhaust valve is firmly held to its seat, the admission valve being also held open. As soon as the level lowers to the point where the water discharge passageways 130 are closed by the float 155, a reduction in water pressure is caused immediately due to the fact that further flow of water is prevented and a further flow of air into the pumping chamber increases the pressure of the same whereby the air pressure is able to move the diaphragm 139 to the left opening the control valve 142 quickly and readily permitting an escape of pressure from the water passageways below the check valve 156. This in turn causes a reduction in the water pressure in the chamber 169 on the left of diaphragm 164 whereby the exhaust valve is thrown open by movement of the diaphragm to the left and the admission valve 178 is thrown to the closed position.

The pressure of the compressed air is immediately depleted in the pumping chamber, the relief valve 42 closing, but the exhaust valve remaining open until the filling stroke is completed. The filling stroke brings the float 55 against the valve seats 134-135 thereby causing a change in pressures upon the diaphragm 164 through either of the three methods referred to or by the conjoint action of one or more of the same, namely, by submergence, by the admission of a small amount of air by leakage, or by the return of a small amount of water by leakage as previously discussed.

It will be obvious that after the movement of a valve is once started, it will be thrown to its extreme position because of the peculiar character of the normally balanced pressures becoming unbalanced. When the float closes off the port 133, the passageways 153 and 170 are closed off with the result that the leakage of a small amount of air

places pressure upon the top of the water 65 which is transmitted through these passageways 130, chamber 131, pipe 24, to the left of diaphragm 139 and to the left of diaphragm 164. Due to the provision of spring 146 the relief valve 142 may have closed previously, but if no spring is employed, the tendency at once is to close this valve and hold the same closed and thereafter the exhaust valve is moved to closed position and the admission valve to open position with a snap action. This snap action is secured primarily because of the lifting of the admission valve 178 and the consequent sudden rise in pressure in the chamber 169 on the left side of the diaphragm 164. 75 80 85

In the embodiment shown in Figures 20 to 29, inclusive, the head member 185 and foot member 186 are connected together by an outer barrel or sleeve 23 similar to the previous embodiment, but on the inside the tension member between said head member and foot member include a second sleeve slightly smaller than the first, this sleeve 187 being formed of a length of seamless tubing threaded at its upper end to a depending portion 188 of the head member 185. At its lower end, the inner tube 187 is threaded to a spider member 189 which has an outer ring upon which the tube is threaded and an inner hub member 190 connected by suitable arms. The hub member 190 is bored out and counter-bored to receive the relief valve 191, this valve being guided in the upper portion of the hub 190 and being adapted to make a tight seat therewith. The lower part of the hub 190 is threaded to receive the hollow stud 192 which has a central bore 193 leading to the outside of the pumping chamber. A nut 194 is threaded to the lower end of the hollow stud 192 thereby holding the head 185 and the foot 186 upon the end of the barrel 23. A plunger member 195 which is provided with cup leather packing 196 and 197 is mounted to slide freely on the end of the working barrel 187. The space between the sleeves 187 and 23 is annular in form. This annular space 198 serves as a water discharge passageway from the working barrel 187 as will be explained later. The guiding piston member 195 carries a poppet valve 199 cooperating with a seat 200 formed in the lower end of the head casting, this seat controlling the exhaust valve passageway 170 which has a port at this point. The valve 199 and seat 200 are centrally located with respect to the bore of the working cylinder 187. The valve 199 is carried upon a stem 201 which stem has a head 202 permitting lost motion of the valve with respect to the piston 195. A spring may be placed in the pocket above the 90 95 100 105 110 115 120 125

head 202 if desired. This play is desirable in order to permit the piston to move down slightly before taking the valve 199 off of the seat 200 in order to insure that shifting of the main valve structure will occur.

The lower end of the piston 195 is provided with a central boss 203 which is adapted to cooperate with the stem 204 of the relief valve 191. The relief valve is held with the stem 204 normally raised above the boss 190 by means of the spring 205. When the piston 195 descends to the lower end of its stroke it strikes the relief valve 204 opening the same and permitting the discharge of a small quantity of water from the water passageway and connections 198 which are in communication with the water discharge pipe below the check valve in the water discharge main. The operation of this control valve 191 permits the shifting of the main valve structure by means of the valve motor, which valve structure and valve motor are similar to the construction shown in the previous embodiment. I have applied similar reference characters to similar parts in the showing of this embodiment so far as these parts are alike or substantially like the corresponding parts in the prior embodiment, and a detailed explanation of the same is not believed to be necessary to a proper understanding of the construction. It will be sufficient to point out that the admission of live air occurs through the connections 122, admission valve 178, passageway 180 to a point immediately above the double piston structure 195. The exhaust passageway 170 which communicates through the annular port 160 controlled by the valve 162 passes through the restricted port 159 and out at the connection 123. The lower end of this exhaust passageway 170 is adapted to be controlled by the valve 199 as previously intimated. The water discharge passageway 206 lies in the upper part of the head above the extension 188 and communicates with the annular space between the two sleeves 187 and 23. This water passageway 206 connects by way of a cross drilled passageway 168 with the diaphragm chamber 169 in the cap 168. This passageway between the water passageway 206 and the diaphragm chamber 169 is shown in dotted lines at 207 in Figure 27.

Both in the present form and in the form previously described I place a small post of metal 208 in the exhaust passageway between the exhaust valve and the top of the pumping chamber for the purpose of providing a suitable foundation for fastening the clamping screw 209 which holds the corresponding diaphragm cap in place.

The operation of the present form of the device is as follows:

Assume that the filling stroke of the pump

as shown in Figures 20 and 21 has just been completed. The double piston structure 195 is at the top of the stroke and the valve 199 has closed off the exhaust passageway 170 by seating against the seat 200. The admission valve 178 is at the present time closed and the exhaust valve 162 is open. The submergence pressure is communicated by way of the annular space 198 to the water discharge passageway 206 and this pressure is transmitted by way of the drilled passageway 207 to the diaphragm chamber 169 where the pressure acts upon the diaphragm 164 to close the exhaust valve and move the admission valve to the open position.

As previously explained, I have provided a slight leak on the valve seat 179 so that if the pump is not supplied with sufficient head of water in submergence to operate the main valves the leakage of air past the admission valve will fill the space above the piston 195 with air, this air being prevented from escaping out the exhaust valve by the valve 199 and the piston 195 begins to move downwardly. In doing so, it imposes a pressure upon the water which is transmitted to the diaphragm chamber 169 and the valves are thereby shifted. Downward motion of the piston 195 without opening the valve 199 can occur because of the lost motion between the head 202 of the valve stem 204 and the follower plate 210 which is adapted to engage said head. As soon as the valve 199 is opened, pressure may enter the exhaust passageway 170, but the exhaust valve is closed. The piston 195 is now driven downwardly as the demand for water permits the same to move, the water being discharged below the end of the cylinder 187 into the annular space 198 from which it moves up to the water discharge passageway 206 past the check valve 156 and out by way of the water discharge pipe 3.

The water discharge check valve as previously explained may be provided with a slight leak so that the reversal may be secured by the return of pressure past the water check valve 156 to the diaphragm chamber 169 and the operation of the main valves by such return pressure from the water system.

As the piston 195 descends it finally strikes the boss 203 against the valve stem 204 of the relief or control valve 191. The water check valve 156 seats and the pressure in the passageway 198 and in the diaphragm chamber 169 is immediately depleted by opening of the relief valve 191 while the pressure on the righthand side of the diaphragm 164, as shown in Figure 20, thereupon immediately overcomes the pressure of the water in the chamber 169 and moves the admission valve 178 to closed position and the exhaust valve 162 to open position. As previously pointed

out the exhaust passageway 159 beyond the diaphragm 164 is restricted so that upward movement of the piston 195 under the normal submergence pressure will tend to maintain a sufficient pressure upon the diaphragm 164 that there will be no tendency to open the admission valve 178 even though there is a small leakage of air past the same. When the piston 195 has moved to the upper position where the valve 199 closes off the port 200, then the submergence pressure or the leakage of water past the check valve or the leakage of air past the admission valve will place pressure upon the water discharge pipe below the check valve 156 and will cause reversal of the main air valve mechanism.

In the present embodiment, the piston 195 becomes the motor for the control valve 191 and is at the same time the level controlled device which governs the operation of the control valve 191 and of the shut-off valve 199 at the upper end of the stroke. In other words, the piston structure 195 assumes the dual function of a level controlled device and of a motor for operating the lower control valve 191. In each of these pumps, the movement of water is fairly rapid and the inertia is sufficient to draw water into the pump before exhaust occurs. In a similar manner, the inertia of the water on filling is sufficient to shift the exhaust valve to closed position and the admission valve to open position.

The admission valve is not an absolute necessity. It will be observed from the foregoing description that its purpose is largely to prevent waste of air and to prevent interference with the filling stroke. A constantly open admission port could be employed particularly on open pumping. It is advisable to use either a restricted inlet port or some means for temporarily shutting off the inflow of compressed air during the filling stroke in order to save air.

The water relief valve which controls the unbalancing of pressures on the main valve motor may be omitted and a constantly open relief port provided particularly on open pumping work. The relief valve shown in Figure 21 may if employed be varied in construction to close with internal pressure if desired as is shown in Figure 2. It may also be mounted in the head of the pump if desired.

I wish to call attention to a peculiar action which occurs in the pump shown in Figures 15 and 16 upon venting the relief valve into the exhaust passageway. When the relief valve 142 is opened, water is first discharged through passageways 157-158 into the restricted exhaust passageway 159. Thereafter the exhaust valve is opened and air at relatively high pressure is driven from the restricted passageway 159 through the

passageways 158-157 through the port of the relief valve along the fluted stem 137 into the water discharge passageway 154 below the check valve 156 below which it lodges. Upon the next stroke, it is forced into the discharge pipe and finds its way into the air spring.

As soon as the pressure in the main chamber drops on the exhaust stroke, the relief valve closes and stops further injection of air. This is a highly desirable result as it maintains the air spring constantly full of air. The small amount sent over at each stroke is not objectionable as it is driven out of the faucets as fast as accumulated since no accumulation occurs while the faucets are closed.

It will be observed that each form of pump waits the filling of the cylinder before the discharge stroke can be made. Likewise in each pump no blowover of air can occur.

I do not intend to be limited to the precise details of construction shown and described and I may vary the embodiment very considerably within the spirit and scope of the invention as defined by the appended claims.

I claim:

1. In a pump, a pump chamber, liquid valves for the pump chamber, a source of motive fluid, a main valve mechanism for the admission and exhaust of the motive fluid, a main motor member for the main valve mechanism, said motor member being subjected on one side to pressure of the liquid which is being discharged from the pump, and on the other side to the pressure of motive fluid employed to expel the liquid from the pump valve, and a relief valve having a motor member independent of said first motor member operated when the pump has completed the discharge stroke for depleting the pressure upon the liquid side of said main motor member to permit said main motor member to shift the main valve mechanism.

2. In a pump, a pump chamber, liquid valves for the pump chamber, a source of motive fluid, a main valve mechanism for the admission and exhaust of the motive fluid, a main motor member for the main valve mechanism, said motor member being subjected on one side to pressure of the liquid which is being discharged from the pump and on the other side to the pressure of motive fluid employed to expel the liquid from the pump, a relief valve operated when the pump has completed the discharge stroke for depleting the pressure upon the liquid side of said main motor member to permit said main motor member to shift the main valve mechanism, a motor member for the relief valve, and a member movable with the liquid level in the pumping chamber for controlling the operation of said relief valve motor member.

3. In a pump, a pumping chamber having liquid inlet and discharge valves, means for supplying motive fluid to the pump, an exhaust passageway having a port, an exhaust valve seating with pressure upon said exhaust port and adapted to be applied to seat when the pump chamber is filled with water, a valve motor member for operating the exhaust valve, said member communicating on one side with the liquid being discharged from the pump, and on the other side with the motive fluid in the pumping chamber, and means controlled by the liquid level for closing off the connection between the latter side of said diaphragm and the pumping chamber, a relief valve for said valve motor member and a balanced pressure motor member adapted to be unbalanced by closure of said connection to cause operation of the relief valve.

4. In combination, a pumping chamber, main valve mechanism for motive fluid, a motor therefor, said motor having a piston member subject to opposed fluid pressures during the discharge of liquid from the pump, a relief valve controlling the pressure upon said piston member, a motor for the relief valve, and means movable with the level of the water in the pumping chamber for causing the operation of the relief valve motor, said relief valve causing a reduction of pressure upon one side of the piston member of the first valve motor to cause it to shift the main valve mechanism.

5. In combination, a pumping chamber, means for supplying motive fluid thereto, an exhaust passageway, an exhaust valve controlling said passageway, and a level controlled member for closing off said passageway upon high level conditions in the pumping chamber before the exhaust valve is closed, and an admission passageway to said chamber independent of said exhaust passageway.

6. In combination, a pumping chamber having a main valve mechanism for motive fluid including an exhaust valve, liquid intake and discharge valves, an exhaust outlet passageway controlled by said exhaust valve, and a high level control valve for closing off said exhaust passageway independently of the exhaust valve, and an admission passageway independent of said exhaust passageway for admitting fluid pressure after said high level valve has closed off said exhaust passageway.

7. In combination, a pumping chamber having a main valve mechanism for motive fluid including an exhaust valve, liquid intake and discharge valves, an exhaust outlet passageway controlled by said exhaust valve, and a high level control valve for closing off said exhaust passageway independently of the exhaust valve, and means

comprising a fluid pressure motor communicating with the interior of the chamber for closing the exhaust valve after said high level control valve has operated to close the exhaust passageway.

8. In combination, a pumping chamber having a main valve mechanism for motive fluid including an exhaust valve, liquid intake and discharge valves, an exhaust outlet passageway controlled by said exhaust valve, and a high level control valve for closing off said exhaust passageway independently of the exhaust valve, and independent means for applying pressure to the liquid in the pumping chamber while said high level control valve closes said exhaust passageway.

9. In combination, a pumping chamber having a water discharge passageway, a check valve for the upper end of said passageway, an air exhaust passageway, a diaphragm forming a wall common to the air exhaust passageway and the water discharge passageway, an exhaust valve controlling the exhaust passageway beyond said diaphragm, said valve being secured to said diaphragm, and means for shutting off the exhaust passageway at high level in the pumping chamber for causing the diaphragm to close the exhaust valve and for shutting off the water discharge passageway at low level to cause the diaphragm to open the exhaust valve.

10. In combination, a pumping chamber having a water discharge passageway, a check valve for the upper end of said passageway, an air exhaust passageway, a diaphragm forming a wall common to the air exhaust passageway and the water discharge passageway, an exhaust valve controlling the exhaust passageway beyond said diaphragm, said valve being secured to said diaphragm, and means for shutting off the exhaust passageway at high level in the pumping chamber for causing the diaphragm to close the exhaust valve and for shutting off the water discharge passageway at low level to cause the diaphragm to open the exhaust valve, and a relief valve operating to reduce the pressure of the water in the water discharge passageway upon the attainment of low level conditions in the pumping chamber.

11. In combination, a pumping chamber, means for admitting motive fluid to the pumping chamber, a water discharge passageway opening into the lower end of the pumping chamber, said passageway having a check valve at the upper end of the chamber, an air exhaust passageway having an exhaust valve controlling the same, a diaphragm communicating on one side with the exhaust passageway below said exhaust valve, and communicating on the other side

with the water discharge passageway below the check valve, said diaphragm being connected to said exhaust valve, and level controlled means for blocking the water discharge passageway upon low level until the exhaust valve opens.

12. In combination, a pumping chamber, means for admitting motive fluid to the pumping chamber, a water discharge passageway opening into the lower end of the pumping chamber, said passageway having a check valve at the upper end of the chamber, an air exhaust passageway having an exhaust valve controlling the same, a diaphragm communicating on one side with the exhaust passageway below said exhaust valve, and communicating on the other side with the water discharge passageway below the check valve; said diaphragm being connected to said exhaust valve, and level controlled means for blocking the water discharge passageway upon low level until the exhaust valve opens, and means operated by said level controlled means for blocking the exhaust passageway on high level conditions in the pumping chamber until the exhaust valve is closed.

13. In combination, a pumping chamber, an exhaust passageway, an exhaust valve, a diaphragm for operating the exhaust valve, a water pressure chamber on one side of the diaphragm, an air chamber on the other side of the diaphragm communicating with the exhaust passageway, and a level controlled member operating on high level to cause a preponderance of water pressure to close the exhaust valve.

14. In combination, a pumping chamber, an exhaust passageway, an exhaust valve, a diaphragm for operating the exhaust valve, a water pressure chamber on one side of the diaphragm, an air chamber on the other side of the diaphragm communicating with the exhaust passageway, and a level controlled member operating on high level to cause a preponderance of water pressure to close the exhaust valve, and operating at low level to cause a preponderance of air pressure.

15. In combination, a pumping chamber, an exhaust passageway, an exhaust valve, a diaphragm for operating the exhaust valve, a water pressure chamber on one side of the diaphragm, an air chamber on the other side of the diaphragm communicating with the exhaust passageway, and a level controlled member operating on high level to cause a preponderance of water pressure to close the exhaust valve, and operating low level to cause a preponderance of air pressure, and means for depleting the water pressure on the water side of the diaphragm.

16. In combination, a pumping chamber, a water discharge passageway, a check valve therefor, an exhaust passageway, an exhaust

valve therefor, a motor member for the exhaust valve subject on one side to the pressure in the water discharge passageway below the check valve, and on the other side to the pressure in the exhaust passageway below the exhaust valve, and level controlled means for creating an operating preponderance of pressure upon the water side of the motor member upon high level to close the exhaust valve.

17. In combination, a pumping chamber, a water discharge passageway, a check valve therefor, an exhaust passageway, an exhaust valve therefor, a motor member for the exhaust valve subject on one side to the pressure in the water discharge passageway below the check valve, and on the other side to the pressure in the exhaust passageway below the exhaust valve, and low level controlled means for creating an operating preponderance of pressure upon the air side of the motor member to cause opening of the exhaust valve.

18. In combination, a pumping chamber, a water discharge passageway, a check valve therefor, an exhaust passageway, an air exhaust valve therefor, a motor member for the exhaust valve subject on one side to the pressure in the water discharge passageway below the check valve, and on the other side to the pressure in the exhaust passageway below the exhaust valve, and means for blocking alternately the water discharge passageway and the exhaust passageway below their respective valves.

19. In combination, a pumping chamber, a water discharge passageway, a check valve therefor, an exhaust passageway, an air exhaust valve therefor, a motor member for the exhaust valve subject on one side to the pressure in the water discharge passageway below the check valve, and on the other side to the pressure in the exhaust passageway below the exhaust valve, and means for blocking alternately the water discharge passageway and the exhaust passageway below their respective valves, said passageways being adapted to be alternately relieved of accumulated pressure to cause operation of the motor member.

20. In combination, a pumping chamber, a water discharge passageway, a check valve therefor, an exhaust passageway, an exhaust valve therefor, a motor member for the exhaust valve subject on one side to the pressure in the water discharge passageway below the check valve, and on the other side to the pressure in the exhaust passageway below the exhaust valve, and low level means for depleting the pressure upon the water side of the motor member to cause operation of the exhaust valve.

21. In combination, a pumping chamber, an exhaust valve, a motor member therefor,

- 5 a pair of fluid passageways leading from the chamber to opposite sides of said motor member, and means controlled by high and low level governing the preponderance of pressures in said respective passageways.
- 10 22. In combination, a pumping chamber, a water discharge outlet, an air exhaust outlet, and means movable with the level for blocking the water outlet when the level of water reaches a predetermined minimum and for blocking the air outlet when the water reaches a predetermined high level, and a valve mechanism controlling the admission and exhaust of motive fluid, said admission valve having a separate passage-way leading into said chamber.
- 15 23. In combination, a pumping chamber, a water discharge passageway, an air exhaust passageway, and means movable with the level of water for blocking the water discharge passageway when the level has reached a predetermined minimum and for blocking the air outlet passageway when the water reaches a predetermined maximum, and means for permitting discharge of pressure from one of said passageways, said means comprising a relief valve and a balanced pressure motor for operating the relief valve.
- 20 24. In combination, a pumping chamber, a water discharge passageway, an air exhaust passageway, level controlled means movable with the level of the water for blocking the water outlet passageway when water has been discharged from the pumping chamber, and for blocking the air exhaust passageway when water has substantially filled the pumping chamber, a motor member operable by differences of pressure in said respective passageways, and a main air valve controlled by said motor.
- 25 25. In combination, a pumping chamber, a water discharge passageway, an air exhaust passageway, means movable with the level for blocking the water discharge passageway when water has been driven from the pump chamber, and for blocking the air exhaust passageway when water has substantially filled the pumping chamber, a motor subject to differences of pressure in said passageways, and a control valve for depleting the pressure in the water discharge passageway to cause operation of the motor.
- 30 26. In combination, a pumping chamber, a water discharge passageway, an air exhaust passageway, a main air valve, a motor member for said air valve adjusted on one side of the pressure in the water discharge passageway and on the other side to pressure in the air exhaust passageway, level control means for blocking the air exhaust passageway to permit pressure to accumulate in the pumping chamber to cause a difference of pressures upon said motor member.
- 35 27. A head for a pneumatic pump comprising a body having air inlet and exhaust passageways therethrough, a transverse bore connecting said passageways, a valve stem closely fitting in said bore, and admission valve on one end of the stem and an exhaust valve on the other end of the stem, said exhaust passageway having a valve seat for the exhaust valve, a diaphragm chamber communicating with the exhaust passageway below said exhaust valve seat, 70 a diaphragm forming a wall of said chamber, and a chamber on the opposite side of the diaphragm adapted to communicate with the water discharge connection of the pump.
- 40 28. A pneumatic pump having a head, said head comprising a body having an air inlet and an exhaust passageway therethrough, a transverse bore in the head, a valve stem fitting in said bore, an admission valve on one end of the stem, an exhaust valve on the other end of the stem, said exhaust passageway having a valve seat for the exhaust valve, a diaphragm chamber communicating with the exhaust passageway below said valve seat, a diaphragm 75 forming a wall of said chamber, a chamber on the opposite side of the diaphragm, a water discharge passageway communicating with said chamber, a water check valve above said communication, and a relief valve 80 above said check valve.
- 45 29. In combination, a pumping chamber, a head member for the chamber, a foot member for the chamber, an exhaust passageway leading to the head of the chamber, an exhaust valve therefor, a movable motor member subjected on one side to the pressure in the exhaust passageway below said valve, a water discharge passageway, a chamber on the other side of said diaphragm 85 communicating with the water discharge passageway, a valve seat for the lower end of the discharge passageway formed on the bottom of the head casting, a level controlled means adapted to cooperate with said valve seat for closing off the exhaust passageway to cause a preponderance of pressure on the water side of said diaphragm, and means controlled by movement of said level controlled member to a point adjacent the foot 90 member for depleting the pressure on the water side of said diaphragm.
- 50 30. In a float for a water pump, a central body of cork, a rubber covering for said cork body, and a valve disk at one end of said float comprising a relatively thin body of soft rubber connected by a narrow flexible neck to the main body of the float, and a filler member surrounding said neck portion and forming a backing for the disk. 100
- 55 31. In a float for a water pump, a central body of cork, a rubber covering for said cork body, and a valve disk at one end of said float comprising a relatively thin body of soft tough rubber connected by a nar- 105

- 65 115
- 70 120
- 75 125
- 80 130

- row flexible neck to the main body of the float, said float having a central axial passageway therethrough, and a guide member mounted in said axial passageway.
32. In combination, a cork body member, a rubber coating for the same, a flexible neck secured to said rubber coating, a flat valve disk secured to said neck, and a ring member surrounding said neck and forming a backing for said valve disk.
33. In combination, a head member, a pumping chamber communicating with the head member, water inlet and discharge check valves for the pumping chamber, main air admission and exhaust mechanism, a motor for operating said mechanism, a motor operated relief valve controlling the operation of the main valve motor, and level controlled means in the pumping chamber, said head member having a valve seat cooperating with the level controlled means on high level to cause shifting of the main valve mechanism to admission position, and a valve seat for the water discharge passageway in the lower part of the pumping chamber cooperating with the level controlled means on low level to cause movement of the main valve mechanism to exhaust position.
34. In a pumping system, an air displacement pump having a pumping chamber, an air spring, a discharge pipe for the pump leading to the air spring, means for supplying compressed air to the pump and a valve for injecting a small amount of air from the pumping chamber into the discharge pipe for each stroke of the pump.
35. In a pump of the class described, an exhaust passageway, an exhaust valve therefor, a water discharge passageway having a check valve, and a valved passageway between the atmospheric end of the exhaust passageway and said water discharge passageway.
36. In a pump of the class described, an exhaust passageway, an exhaust valve therefor, a water discharge passageway having a check valve, and a valved passageway between the exhaust passageway and said water discharge passageway, said connection extending from a point in the exhaust passageway on the atmospheric side of the exhaust valve to a point in the water discharge passageway below the check valve.
37. In combination, a pressure chamber having means for admitting compressed air and an exhaust valve seating with pressure, a piston connected with the exhaust valve and subjected on one side to the fluid pressure controlled by the exhaust valve, a pump barrel, the other side of said piston being subjected to the same pressure as that of the water in the pump barrel, means to permit emptying of the pump barrel and means controlled by the emptying of the pump barrel for relieving the pressure on the said other side of the piston, said means comprising a pilot valve for said piston, a motor for said pilot valve and a float valve controlling said motor.
38. In combination, a pressure chamber having means for admitting compressed air and an exhaust valve seating with pressure, a piston connected with the exhaust valve and subjected on one side to the fluid pressure controlled by the exhaust valve, a pump barrel, the other side of the piston being subjected to the same pressure as that of the water in the pump barrel, means to permit emptying of the pump barrel, and means controlled by the emptying of the pump barrel for relieving the pressure in said other side of the piston, an admission valve, and means actuated upon filling of the pump barrel for cutting of connection between the admission and the exhaust valve.
39. In combination, a pump having admission and exhaust ports for motive fluid, an admission valve and an exhaust valve for said ports, and means lying between said ports and being responsive to the pump strokes for independently cutting off communication between the admission valve and the exhaust valve.
40. In a pump, a valve head comprising an admission passageway and an exhaust passageway, a transverse bore intersecting said passageway and forming at its ends ports having valve seats for the respective passageways, a valve stem in said transverse bore, said stem being longer than said bore, and poppet valve members on the ends of said stem for obstructing said ports one at a time, said valves each seating with superior pressure.
41. In a pump, a valve head comprising an admission passageway and an exhaust passageway, a transverse bore intersecting said passageway and forming at its ends ports having valve seats for respective passageways, a valve stem in said transverse bore, said stem being longer than said bore, and poppet valve members on the ends of said stem for obstructing said ports one at a time, said valves each seating with superior pressure, and a motor member for moving said valve members alternately off and upon seat.
42. In a pump, a head member having an admission passageway leading therethrough, an exhaust passageway also leading therethrough, a motor chamber having a diaphragm, and a transverse bore connecting said passageways and said chamber, a valve stem connected to said diaphragm lying in the transverse bore, and facing poppet valves on the ends of said stem for controlling said passageways alternately.
43. In a pump, a head member having an admission passageway leading therethrough, an exhaust passageway also leading there-

- through, and a transverse bore connecting said passageways, said admission passageway comprising an outer portion, an inner portion, and a transverse portion extending 5 co-axially with said transverse bore and having a valve seat at the point where the outer portion of the admission passageway joins the transverse portion, said exhaust passageway comprising an inner portion, an outer portion, and a transverse portion, said transverse portion being co-axial with the transverse bore and having a valve seat at the junction of the inner portion and the transverse portion, a valve stem lying in said 10 transverse bore, and poppet valve members cooperating with said valve seats.
44. In a pump, a head member having an admission passageway leading therethrough, an exhaust passageway also leading there- 20 through, and a transverse bore connecting said passageways, a valve stem lying in the transverse bore, valves on the ends of said stem for controlling said passageways alternately, the inner end of the exhaust passageway having a valve seat and a valve 25 operated at the end of the filling stroke of the pump for closing said exhaust passageway independently of the valves on said stem.
45. In a pump, a head member having an admission passageway leading therethrough, an exhaust passageway also leading there- 30 through, and a transverse bore connecting said passageway, said admission passageway comprising an outer portion, an inner portion and a transverse portion, said transverse portion having a valve seat at the point where the outer portion of the admission passageway joins the transverse portion, said valve 35 seat being substantially co-axial with the transverse bore, said exhaust passageway comprising an inner portion and an outer portion, and a transverse portion and having a valve seat at the junction of the inner portion and the transverse portion said valve seat being substantially co-axial with said transverse bore, said stem having poppet valve members cooperating with said valve seats, a diaphragm chamber being formed in 40 communication with the inner portion of the exhaust passageway and a diaphragm forming one wall of the chamber, said diaphragm being connected to said valve stem.
46. In a pump, a head member having an admission passageway leading therethrough, an exhaust passageway also leading there- 45 through, and a transverse bore connecting said passageways, said admission passageway comprising an outer portion, an inner portion and a transverse portion, said transverse portion having a valve seat at the point where the outer portion of the admission passageway joins the transverse portion, said valve seat being substantially co-axial with 50 the transverse bore, said exhaust passageway
- comprising an inner portion and an outer portion, and a transverse portion and having a valve seat at the junction of the inner portion and the transverse portion, said valve seat being substantially co-axial with 55 the transverse bore, a valve stem lying in said transverse bore, said stem having poppet valve members cooperating with said valve seats, a diaphragm chamber being formed in communication with the inner portion of the exhaust passageway and a diaphragm forming one wall of the chamber, said diaphragm being connected to said valve stem, a second diaphragm chamber on the opposite side of said diaphragm and being connected to the water space of the pump. 60
47. In a pump a pumping chamber, a water discharge outlet, a valve therefor, an air exhaust outlet, a valve therefor, means movable with the level of water in the chamber for alternately blocking said outlets at the end of corresponding pump strokes, a balanced pressure motor communicating with the chamber by way of each of said outlets on the chamber side of the respective valves 65 therefor.
48. In a pump a pumping chamber, a water discharge outlet, a valve therefor, an air exhaust outlet, a valve therefor, means movable with the level of water in the chamber for alternately blocking said outlets at the end of the corresponding pump strokes, a balanced pressure motor communicating with the chamber by way of each of said outlets on the chamber side of the respective valves 70 therefor, a second balanced pressure motor also communicating with said chamber, and a relief valve communicating with one of said outlets, said relief valve being actuated by said second motor. 75
49. In combination a pumping chamber, a water discharge outlet, an air discharge outlet, a main air valve, means movable with the level of water in said chamber for alternately blocking said outlets at the end of the corresponding pump strokes, and a motor actuated by the internal pressure in the chamber when said means blocks the air discharge outlet for operating the main valve 80 to admit pressure to said chamber. 100
50. In a pump of the class described, a head member having a generally vertical air admission passageway, a generally vertical air exhaust passageway and a motor chamber, valve ports for said admission and exhaust passageways aligned axially with the motor chamber, valves for said valve ports, a diaphragm for said motor chamber, said head having a horizontal transverse opening 105 connecting said ports and said chamber and common stem lying in said transverse opening and connecting said diaphragm and said valves for joint operation. 110
51. In a pump having a pumping chamber, a head member having generally vertical 115

air admission and exhaust passageways, said passageways having aligned horizontal portions including valve seats, valves for said seats, a motor chamber having a diaphragm, 5 a horizontal stem connected to said diaphragm and to said valves for obstructing said ports alternately, and means actuated at high level and at low level to govern the fluid pressures upon opposite sides of the 10 diaphragm for shifting said valves.

52. In a pump a pumping chamber, a head member having air admission and exhaust passageways, said passageways having aligned transverse portions including valve 15 seats, an air admission valve and an air exhaust valve, a motor having a diaphragm and chambers on each side thereof for applying fluid pressure to the diaphragm, a central discharge pipe through the pumping 20 chamber, and valve means for high and low level for applying fluid pressure alternately upon opposite sides of the diaphragm for actuating the air valves, said valve means including a float guided upon said water discharge 25 pipe.

53. In a pump a pumping chamber, a head member having air admission and exhaust passageways, said passageways having aligned transverse portions including valve 30 seats, an air admission valve and an air exhaust valve, a motor having a diaphragm and chambers on each side thereof for applying fluid pressure to the diaphragm, a central discharge pipe through the pumping chamber, and valve means for high and low level 35 for applying fluid pressure alternately upon opposite sides of the diaphragm for actuating the air valves, said valve means including a float guided upon said water discharge 40 pipe, and means upon opposite ends of said float for governing the valve means.

54. In a pump, a valve head having a motor diaphragm, a stem for the diaphragm, an air admission passageway, an air exhaust 45 passageway, said passageways having aligned valve ports, poppet valves on said diaphragm stem for controlling said ports, a transverse bore through the head providing a guide for said stem and caps on the sides 50 of the head for closing the outer ends of said transverse bore.

55. In a pump a valve head having an air admission passageway provided with a valve port, an air exhaust passageway provided 55 with a valve port, a transverse bore through the head passing through said valve ports, valves for said ports, a common stem for said valves lying in said bore, a motor diaphragm closing one end of the bore and 60 being connected to said stem.

56. In a pump a valve head having an air admission passageway provided with a valve port, an air exhaust passageway provided 65 with a valve port, a transverse bore through the head passing through said valve ports,

valves for said ports, a common stem for said valves lying in said bore, a motor diaphragm closing one end of the bore and being connected to said stem, the outer end of the bore under the diaphragm being enlarged to form a pressure chamber. 70

57. In a pump a valve head having an air admission passageway provided with a valve port, an air exhaust passageway provided with a valve port, a transverse bore through 75 the head passing through said valve ports, valves for said ports, a common stem for said valves lying in said bore, a motor diaphragm closing one end of the bore and being connected to said stem, the outer end 80 of the bore under the diaphragm being enlarged to form a pressure chamber, a cap covering the diaphragm and forming a pressure chamber for the outside of the diaphragm. 85

58. In a pump a valve head having an air admission passageway provided with a valve port, an air exhaust passageway provided with a valve port, a transverse bore through 90 the head passing through said valve ports, valves for said ports, a common stem for said valves lying in said bore, a motor diaphragm closing one end of the bore and being connected to said stem, the outer end 95 of the bore under the diaphragm being enlarged to form a pressure chamber, a cap covering the diaphragm and forming a pressure chamber for the outside of the diaphragm, and a screw plug closing the opposite end of the bore and providing access to 100 the adjacent end of the stem.

59. In a pump a pump barrel, a head member, a foot member, a discharge pipe centrally placed in the barrel and tying the head and foot members together upon the 105 barrel, valve means for controlling the pump strokes mounted in the barrel adjacent the head and adjacent the foot, and a traveling float guided on the discharge pipe for controlling the valve means. 110

60. An automatic montejus comprising a receptacle having a liquid inlet provided with a check-valve and a liquid outlet, a source of compressed air, means for continuously supplying a limited quantity of compressed air to said receptacle, and means 115 subject to the pressure in said receptacle for opening communication between said source of compressed air and said receptacle when a predetermined pressure has been established. 120

61. An automatic montejus comprising a receptacle having a liquid inlet provided with a check valve and a liquid outlet, a source of compressed air, means for continuously supplying a limited quantity of compressed air to said receptacle, a vent port through which such air may escape, means for preventing the escape of air through said vent port when the liquid reaches a prede- 125 130

termined level, and means subject to the pressure in said receptacle for opening communication between said source of compressed air and said receptacle when a predetermined pressure has been established.

62. A regulating valve comprising a casing having an inlet and an outlet opening, a valve seat and a valve, a by-pass around said valve seat, a chamber in said casing, a port

in said casing extending from said chamber to the outlet side of said casing, and means in said chamber operative upon a predetermined increase in pressure for opening said valve.

In witness whereof, I hereunto subscribe my name this 7th day of September, 1921.

BURTON S. AIKMAN.
